Inventor:
Albert Kontsek

UNITED STATES PATENT OFFICE.

ALBERT KONTSEK, OF MEADOWLANDS, PENNSYLVANIA.

PROCESS OF LOOSENING (OPENING) TIN PLATES FOR COLD ROLLING.

Application filed August 17, 1921. Serial No. 493,144.

To all whom it may concern:

Be it known that I, ALBERT KONTSEK, a citizen of the United States, residing at Meadowlands, in the county of Washington 5 and State of Pennsylvania, have invented certain new and useful Improvements in Processes of Loosening (Opening) Tin Plates for Cold Rolling; and I do hereby declare the following to be a full, clear, 10 and exact description of the invention, such as will enable others skilled in the art to which it appertains to make and use the same.

This invention relates to a method and 15 apparatus for opening or separating metal plates or sheets such as are usually packed or piled one upon another in the process of manufacture, and more particularly tin plates, the edges of which, during the 20 hardening process, melt somewhat, so that the plates come out of the ovens more or less soldered together, and can be separated or forced apart only after pounding them with heavy hammers or heavy iron bars, 25 and by the hammering and beating the plates are bent, so that they may be more easily separated.

The object of my invention is to dispense 30 with the slow, cumbersome and expensive process of separation by hand, and to provide simple and efficient electro-mechanical means for easily and quickly accomplishing the desired result, at comparatively little expense, and more efficiently and without injury to the plates by hammering and beating them.

The invention will first be hereinafter 40 more particularly described, with reference to the accompanying drawings, which are to be taken as a part of this specification, and then pointed out in the claims at the end of the description.

In said drawings, Fig. 1 is a side elevation of a pile or column of tin plates with 45 an insulator and electro-magnet resting thereon for effecting a separation of said plates by energizing said magnet;

Fig. 2 is a similar view showing a modified form of insulator;

Fig. 3 is a perspective view of the insulator shown in Fig. 1; and

Fig. 4 is a perspective view of the insulator shown in Fig. 2.

In practicing my invention, after the 55 plates are removed from the hardening ovens

and cooled off, I place on top of a pile, column, or batch of plates, denoted by the letter A, either at one end, or about midway of the length of the pile, an insulator B, Fig. 1, or B¹, Fig. 2, and on top of the insulator I place an ordinary electro-magnet M, connected in circuit with a source of electric supply, for energizing the same, and having great power or sufficient power to adapt it to perform the desired function 60 on the pile of plates to be separated. The insulator B may consist of a block of wood, flat on the under side or base thereof, and enlarged toward one end in wedge-shaped form, said enlarged end being rounded, as 65 at b. It is preferably made in two parts, of dry wood, as shown in Fig. 2, the lower part b¹ consisting of a piece of board having flat upper and lower sides, and the upper part b² consisting of a block of wood in 70 the form of a wedge, or having converging upper and lower sides and rigidly secured to 75 said base.

The insulator B¹ is constructed with parallel top and bottom b³ and b⁴ and rounded 80 sides b⁵ and b⁶, as shown, and the magnet rests on its flat upper side or top.

The insulating blocks, whether made in one piece, or two or more pieces, rigidly secured together, are designed to be constructed in different sizes, according to the size and width of the plates to be separated. 85

In operation, the parts being assembled, as shown in Fig. 1, and current turned on, the magnet will be energized and caused to quickly loosen the free edges of the uppermost plate, which are not covered by the insulator, and draw or pull the plate partly away from the next underlying plate, or column of plates, whereupon the current is 90 interrupted and again turned on, to separate the next succeeding plate in the pile or column of plates, and so on, in quick succession, until the desired number of plates or such number as the magnet has power to 95 separate are separated and pulled apart in the manner shown in Fig. 1, and thereupon a piece of board C, several inches thick, is put between the separated and still adherent plates at one side of the column, and the 100 electro-magnet raised up and the insulator placed on the other side of the column, and the process repeated until all of the partly separated plates are entirely separated. The 105 separated plates may then be removed, ready 110

for cold rolling, and the tearing off of the next layer of plates proceeded with and finished in the manner stated. The tearing off process is repeated as many times as may be necessary to separate a certain number or the entire batch or column of plates. A dozen or more plates may be separated by a powerful electro-magnet to the extent indicated before applying it on the other side of the column, and before removing the separated plates and proceeding with the tearing off process on the remaining plates of a large pile or column.

When the insulator is placed between the ends or sides of the plates, as shown in the modification, Fig. 2, the magnet will act on opposite ends or sides so as to pull and raise the ends or sides of the plates on both sides of the insulator simultaneously, and when a dozen, more or less, plates have been so acted upon, the insulator is then placed across the width or length of the plates at right angles to its first position, whereupon the operation is continued until the remaining unloosened side or end portions of the plates are loosened and separated, thus finishing the operation.

I do not broadly claim the method of separating metal plates by the action of an electro-magnet or magnets, but what I claim as new and desire to secure by Letters-Patent of the United States is:

1. The herein described method of separating tin plates, or the like, which consists in arranging a batch of plates in juxtaposition to an electro-magnet, then energizing the magnet, thus causing the outer or uppermost plate to be torn loose and pulled partly away from the next underlying plate, then again energizing the magnet so as to cause the next succeeding plate to be loosened and drawn away from the plate underlying the same, and so on, from plate to plate, in succession.

2. The herein described method of separating tin plates, or the like, which consists in arranging a batch of plates in juxtaposition to an electro-magnet and interposing an insulating block, then energizing the magnet, thus causing the outer or uppermost plate to be torn loose and pulled partly away from the next underlying plate against the pressure of said block, then again energizing the magnet so as to cause the next succeeding plate to be loosened and drawn away from the plate underlying the same, and so on from plate to plate, in succession.

3. The herein described method of separating tin plates, or the like, which consists in arranging a batch of plates in juxtaposition to an electro-magnet and interposing an insulating block having a rounded edge,

then energizing the magnet, thus causing the outer or uppermost plate to be torn loose and pulled partly away from the next underlying plate, against the rounded edge of said block, then again energizing the magnet so as to cause the next succeeding plate to be loosened and drawn away from the plate underlying the same, and so on, from plate to plate in succession.

4. The herein described method of separating tin plates, or the like, which consists in arranging a large pile or column of plates in juxtaposition to an electro-magnet with an insulating block on the uppermost plate between it and said magnet, then energizing the magnet intermittently, whereby several plates are torn loose and pulled partly away from the next underlying plate in succession, then shifting the position of the insulator and subjecting the remaining unloosened portions of the plates successively to the action of the magnet until the desired number are separated.

5. The herein described method of separating adherent metal plates, which consists in arranging a pile or column of plates in juxtaposition to an electro-magnet resting on an insulator between it and the pile of plates, then energizing the magnet, whereby the uppermost plate is torn loose and pulled partly away from the next underlying plate, then again energizing the magnet, whereby the latter plate is torn loose and pulled partly away from the next succeeding plate, and so on, successively, from plate to plate, then shifting the position of the insulator so that the magnet may act on the remaining unloosened portions of the plates and again energizing said magnet intermittently until the partly separated plates are completely separated.

6. The herein described method of separating adherent tin plates, or the like, which consists in arranging a pile or column of plates and an electro-magnet in slightly separated relation and interposing an insulating block, then energizing the magnet, whereby side or end portions of the uppermost plate are torn loose and pulled away from the next underlying plate, then subjecting the latter plate to the action of said magnet, whereby side or end portions thereof are torn loose and pulled away from the next succeeding plate, and so on, successively, until a batch of plates are partly separated, then arranging the magnet so as to act upon the other side or end portions of said plates and subjecting the remaining unseparated portions of the plates successively to the action of said magnet.

ALBERT KONTSEK.
